COMBINATION BAG HOLDING AND EMPTYING DEVICE

Vernon J. David, Durham, Kans.

Application June 21, 1954, Serial No. 31,097

Term of patent 14 years

(Cl. D55—1)

FIG. 1.

FIG. 2.

FIG. 5.

FIG. 3.

FIG. 4.

Figure 1 is a front perspective view of a combination bag holding and emptying device embodying my new design, in its position as a bag holder;

Figure 2 is a side perspective view of the design;

Figure 3 is a rear perspective view of the design in its position as a bag emptier;

Figure 4 is a sectional view taken on line 4-4 of Figure 3; and

Figure 5 is a sectional view taken on line 5-5 of Figure 1.

I claim:

The ornamental design for a combination bag holding and emptying device, as shown.
